Primary Examiner — Mark Goodwin*(74) Attorney, Agent, or Firm* — Quarles & Brady LLP(57) **CLAIM**

The ornamental design for a work vehicle, as shown and described.

DESCRIPTION

FIG. 1 is a top, rear, left perspective view of a work vehicle embodying our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a top, rear, left perspective thereof view showing different work vehicle environment.

The broken line representations in the figures show unclaimed environment or boundaries, and thus form no part of the claimed design.

The nature of this product is a work vehicle, such as a skid steer loader, including boom arms and engine cover parts therefor.

1 Claim, 7 Drawing Sheets(56)
